UNITED STATES PATENT OFFICE

2,274,415

TELEMETERING SYSTEM

Richard G. Jewell, Lynn, Mass., assignor to General Electric Company, a corporation of New York

Application October 1, 1940, Serial No. 359,290

5 Claims. (Cl. 172—239)

My invention relates to a remote indicating system and concerns particularly arrangements for electrically transmitting indications of angular movement.

It is an object of my invention to provide a compact, reliable, simplified telemetering system and a receiver therefor.

A further object of my invention is to provide a telemetering system which utilizes a small amount of electrical energy, which may be operated on direct current, and which requires only two insulated conductors between the transmitter and receiver, permitting one side of the current source to be grounded.

Other and further objects and advantages will become apparent as the description proceeds.

In carrying out my invention in its preferred form I provide a transmitter in the form of a potentiometer with a movable tap, and a receiver in the form of an annular core, with a light permanent-magnet rotor and oppositely wound field windings on the core. The arrangement is such that the current in the field winding produces a magnetic flux diametrically crossing the core and changing in angular direction with changes of the potentiometer setting. The rotor is caused to take up a center position when the potentiometer tap is in its middle position and to deflect with shifting of the potentiometer tap to one side or the other.

The invention will be understood more readily from the following detailed description when considered in connection with the accompanying drawing and those features of the invention which are believed to be novel and patentable will be pointed out in the claims appended hereto. In the drawing, Fig. 1 is a circuit diagram schematically representing one embodiment of my invention showing the position of the apparatus with the pointers at the transmitting and receiving ends in the center position. Fig. 2 is a diagram of the apparatus of Fig. 1 showing the condition with the pointers at one extreme end of their scales, Fig. 3 is a schematic diagram of a modified form of receiver for the system shown in Figs. 1 and 2, and Fig. 4 is a view of a section through the core cut by a plane 4—4'. Like reference characters are utilized throughout the drawing to designate like parts.

In the drawing, the transmitter is designated as a whole by the reference numeral 11 and the receiver is designated as a whole by the reference numeral 12. A source of direct current 13 is employed for energizing the apparatus, and a

pair of insulated conductors 14 and 15 is provided extending between the transmitter 11 and the receiver 12. A third electrically conducting path is required, which may take the form either of a conductor 16 which need not be insulated or may be formed by the metallic framework of the structure on which the telemetering system is mounted. In this latter case suitable terminals of the transmitter 11, receiver 12, and the current source 13 would be grounded to such framework. The current source 13 may be located either at the transmitting station 11, at the receiving station 12 or at some other point, as found most convenient in any particular installation.

The telemetering apparatus illustrated is not limited in its usefulness to any particular class of service, but owing to its lightness, compactness and low energy requirements, it is well adapted to use on aircraft for transmission of instrument measurements and the indications of angular positions. One of the applications for which it is adapted, for example, is the remote indication of the position of landing gear for which dials may be used, such as illustrated in Patent 2,181,803—Faus—Remote indicator, and Design Patent 112,743—Haven—Design for an airplane landing indicator. Other applications are for transmitting to the cockpit of the airplane, measurements of engine speed and engine temperature, fuel quantity, and the like. The particular forms of pointers, dials, and scales employed are not a part of my present invention and such parts of the apparatus are, therefore, not shown in the drawing, which illustrates only the internal mechanism of the transmitter and receiver.

The transmitter is in the form of a rheostat or potentiometer consisting of a resistor 17 and an adjustable tap therefor 18. The resistor 17 may be either straight or curved according to whether the indicator at the transmitting station moves along a straight line or angularly, but for the sake of illustration a resistor 17 is shown which is shaped in the form of an arc of a circle, or which may have contacts arranged on the arc of the circle. The embodiment of the invention represented in the drawing is a system for transmitting an angular indication over a 120 degree scale from a transmitting point to a receiving point. Accordingly, the resistance 17 has an arc of 120 degrees. The transmitter 11 has three terminals. There are terminals 19 and 20 at the ends of the resistor 17 and one of these terminals, for example, the latter may

be grounded, as illustrated. A third terminal 21 of the transmitter 11 is electrically connected to the movable tap 18 which is preferably carried by an indicator arm 22 having a center of rotation at the center of the arc of the resistor 17. The terminal 19 is connected to the insulated conductor 15 and the terminal 21 is connected to the insulated conductor 14. The current source 13, which may be a battery of dry or storage cells, has a pair of terminals 23 and 24, one of which may be grounded. In the arrangement illustrated, the terminal 24 is a negative terminal and is grounded. The positive terminal 23 of the current source 13 is connected to the insulated conductor 15 leading from the ungrounded end of the transmitter resistor 17.

The receiver 12 comprises a rotor 25 and a stator, comprising an annular core 26 carrying a pair of stator or field windings 27 and 28.

The rotor 25 is composed of high-coercive-force permanent-magnet material and is magnetized transversely to the axis of rotation, is preferably mounted concentric with the annular stator core 26, and has a circular cross section, being cylindrical in the apparatus represented by the illustrative drawing. The polarity of the permanent magnet rotor is represented by the letters N and S and the direction of the magnetic field produced by the rotor magnetization is represented by an arrow 29. For reasons which will be explained hereinafter, it is preferable to arrange the design in such a manner that the line of magnetization is substantially as shown in Fig. 1 when the pointer or dial carried by the rotor is approximately in the middle of its scale range in the case of uniform scale distribution. According to the type of indicator or instrument to be employed, a suitable pointer, target or dial is secured to the rotor 25 and it is represented in the drawing by a fragmentary pointer 30, the apparatus being so arranged for the sake of convenience in explanation that the pointer 30 of the receiver and the arm 22 of the transmitter have the same angular position.

For the sake of lightness, high torque and high damping, the rotor 25 is preferably composed of a material having relatively low density, but high coercive force, and a strong tendency to retain precisely a given line of magnetization. For example, sintered oxide may be employed composed of magnetite, ferric oxide and cobaltic oxide, substantially in the proportions of 43.6% magnetite, 30.1% ferric oxide and 26.3% cobaltic oxide, respectively, such as that described in the patent of Ralph G. Arey and Harold T. Faus, Number 2,101,665, granted December 7, 1937, and assigned to the same assignee as the present invention. When composed of this material, the rotor consists of a solid unlaminated block of circular cross section which is polarized across a diameter thereof. The material is prepared and magnetized as follows:

Mix together finely powdered magnetite, ferric oxide and cobaltic oxide in the proportions of 43.6% magnetite, 30.1% ferric oxide, and 26.3% of cobaltic oxide. Mold the mixture in the shape desired under pressure of from three to five tons per square inch. Remove from mold and heat in an atmosphere of nitrogen or air for two or three hours at about 1000 degrees C. and allow to cool. Then reheat to about 520 degrees C. in a special furnace placed in the air gap of a direct-current electromagnet with a field of about 3000 H. With the field on, lower the temperature to about 75

300 or 320 degrees C. and hold in the field within this range of temperature for about three-quarters of an hour. Then allow to cool in the field to below 100 degrees C. The material may then be machined or ground to shape, if necessary. An unusual property of this material which I have discovered and which makes it particularly suitable for telemetric receiving is that although it may be magnetized in a given transverse direction while hot it is virtually impossible thereafter to shift the line of magnetization to a different angle without raising the temperature to about 300 degrees. It is believed that the materials described in United States Patents No. 1,997,193 and No. 1,976,230 to Kato et al. will also be useful for the rotor material on some forms of the apparatus although I have found that the sintered oxide material which I have described, produces telemeter receivers with the best performance.

Such material after being magnetized, in addition to being a permanent magnet of exceptionally high coercive force and adequate, although lower, residual induction than some of the common permanent magnet materials, has other remarkable properties. It has a resistance between 600,000 and 1,000,000 ohms per cm. cube and is thus practically an insulator. It is hard and of a gray slate color. It is very light in weight as compared to other magnetic materials, having a specific gravity of approximately one-half that of ordinary steel. The coercive force of the material prepared as previously described is between 700 and 1000 oersteds and the residual induction is about 2000 lines per square centimeter. The available magnetic energy of the material per unit volume is approximately 1,000,000 measured in terms of the maximum value of the product of flux density and field strength in lines per square centimeter or Gausses and in Gilberts per centimeter respectively. Accordingly, the ratio of the magnetic energy per unit volume to the specific gravity or the magnetic energy per unit mass is over 2,000,000 measuring specific gravity in terms of that of steel. Likewise the ratio of residual induction to specific gravity exceeds 4000.

Since the line of polarization is very definite and fixed and does not shift, the scale need not be recalibrated and reset in case the windings should be deenergized and reenergized with the rotor in a different position. As a cylindrical magnet composed of the sintered oxide material behaves just as if it were a thin line permanent magnet, the position assumed by the pointer is very definite and the exact position may be relied upon as an accurate indication of the measurement transmitted.

The core 26 may be in the form of an annulus having a rectangular cross section, as shown in Fig. 4, but the particular shape of cross section is not essential to carry out the invention. It is desirable, however, to provide an air gap 31 in the annulus along the diameter along which the direction of rotor magnetization 29 lies when the rotatable pointer 30 is substantially in the middle of its scale range in the case of a uniformly calibrated scale or one which is symmetrical. It will be understood, of course, that the pointer 30 need not be in line with the line of magnetization 29, as the position of the pointer with respect to the rotor depends upon the desired angular position of the scale (not shown) with respect to the stator. As will be explained more in detail hereinafter, the air gap 31 serves to provide the op-

timum relationship between the reluctance of a magnetic circuit passing circularly through the annulus 26 and passing diametrically across it. For the purpose of increasing the deflection-producing torque and the damping, and giving good shielding with low losses, the core 26 is preferably composed of magnetic material having high permeability and low hysteresis, such as a nickel-iron alloy containing 78½% nickel.

The field windings 27 and 28 are connected in series between a pair of stator terminals 32 and 33, one of which, for example, the latter, may be grounded. The junction point of the windings 27 and 28 is brought out to form a third terminal 34. The terminals 32, 33 and 34 serve as the receiver terminals. One stator coil is connected oppositely with respect to the other so that current in flowing from terminal 32 to terminal 33 produces a polarity of the coil 27 tending to cause flux to pass circularly in the opposite direction to the flux produced in the core 26 by the polarity of the coil 28. The ungrounded end receiver terminal 32 is connected to the conductor 18 to which the ungrounded side of the current source 13 is connected, and the coil junction terminal 34 of the receiver 12 is connected to the conductor 14 to which the tap 18 of the transmitter 11 is connected.

The principle of operation of the telemetering system will most readily be understood by first considering the parts in the position shown in Fig. 1. It will be apparent that an electrical circuit is formed from the positive terminal 23 of the battery 13, through the conductor 18, coil 27, the coil 28, back through the ground 16, to the negative terminal 24 of the current source 13. There is likewise a parallel circuit from the positive terminal 23 through the conductor 18, the resistor 17 and ground to the grounded terminal 24 of the current source 17. The conductor 14 has no effect on the circuit since it is connected between the middle point on the resistor 17 to the junction terminal 34 of the receiver 12, it being understood that for uniform or symmetrical scale calibration the coils 27 and 28 are identical, with the same resistance.

Accordingly, the opposing fluxes produced by the coils 27 and 28 in the core 26 meet at the ends of the vertical diameter of the core 26 and pass downward diametrically from the upper point on the annulus toward the air gap 31, as shown by the flux lines 35. With the connections shown, the upper point of the annulus has north polarity and the point adjacent the air gap has south polarity so that the rotor 25 takes the position indicated with the south pole at the top and the north pole at the bottom, and the line of magnetization 29 vertical.

If the indicating arm 22 of the transmitter 11 is shifted in one direction or the other, the symmetry of the electrical circuit is upset and one or the other of the coils of the receiver is partially short circuited. Looked at another way, the relative values of two series voltages applied to the coils 27 and 28 vary with the position of the tap 22. For example, as illustrated in Fig. 2, if the arm 22 is moved to the extreme left-hand position, namely 60 degrees to the left from center, in the design illustrated, the left-hand receiver coil 27 is short circuited, receives zero voltage and becomes dead so that all the flux acting in the receiver is produced by the coil 28. Owing to the fact that the air gap 31 produces some reluctance in the iron circuit of the core

26, an appreciable leakage flux crosses the central opening of the annulus 26, as illustrated by the flux lines 35' in Fig. 2. The flux path at the center of the annulus is along a diagonal diameter the ends of which are half way between the coil 28 and air gap 31. It will be understood that the size of the air gap 31 is made such, in relation to the inside diameter of the annulus 26 and the magnetic properties of the core material, that the diametral flux is substantially of the same strength as in the condition of Fig. 1. The coils 27 and 28 are so mounted in the specific embodiment illustrated that their centers are spaced approximately 120 degrees, and symmetrical with respect to the vertical diameter of the annulus 26. Consequently, the direction of the flux crossing the center of the annulus 26 is substantially along a line, 60 degrees from the vertical, upward to the left, when the coil 27 is short circuited. Accordingly, the rotor 25 is deflected 60 degrees with its line of magnetization 29 following the flux lines in the center of the annulus 26. Consequently, the rotor pointer 30 is shifted to the left 60 degrees, taking up the position shown in Fig. 2. It will be understood that intermediate positions between center and extreme left will be taken up by the pointer 30 when the transmitter-indicator arm 22 is moved to positions between extreme left and the center position, and likewise the corresponding positions to the right are taken up when the arm 22 is shifted to the right of center.

It will be understood that the best dimensions and mechanical and electrical relationships for the various parts of the system will depend upon the type of service to which the telemetering system is to be applied. My invention obviously is not limited to any particular numerical values. However, I have found that in instruments for use on aircraft, very satisfactory results are obtained in which specific values are approximately as follows: the diameter of the sintered oxide rotor 25, $\frac{1}{4}$ inch; axial length $\frac{1}{4}$ inch; inside diameter of the annular core 26, about 1 inch; cross section (Fig. 4) $\frac{1}{16}$ inch square; length of air gap 31 in the core, between .01 and .02 inch; core composed of the nickel-iron alloy known by the trade-name Permalloy; potential difference of the current source 13, 10-15 volts D. C.; coils 27 and 28, about 530 ohms, each with 2,000 turns and a combined energy consumption of about $\frac{1}{6}$ watt when the rotor is in the center position; resistor 17, total resistance about 200 ohms, energy consumption of about 1 watt.

Owing to the high magnetic energy and residual magnetization of the sintered oxide rotor, a minimum flux density of 250 Gausse, due to the rotor, is maintained in the space between the rotor and the annular core 26. Consequently, a relatively small magnetomotive force need be supplied by the stator. In other words, very small field current suffices. Owing to the fact that the greater magnetomotive force is produced by the rotor, a strong positive damping action may be provided, if desired, as well as high torque.

Damping may be produced by providing a damping cup 36, as illustrated in Fig. 3, the cup being composed of a suitable, highly conductive material, such as copper. It will be understood, however, that a certain amount of damping is provided by the fact that the circuits of the coils 27 and 28 are closed through the resistance 17.

It will be observed that the flux produced by the stator, that is, by the field windings 27 and

28, is primarily for the purpose of directing the rotor, and that the greater portion of the magnetic energy is provided by the rotor flux. In this way, a light, compact, low-loss system may be provided for aircraft in which weight is at a premium and it is highly desirable to utilize a system having current conducting windings which carry but little current and consequently have relatively little heat loss, in order that fine wire and compact units may be employed without danger of overheating.

I have herein shown and particularly described certain embodiments of my invention and certain methods of operation embraced therein for the purpose of explaining its principle and showing its application but it will be obvious to those skilled in the art that many modifications and variations are possible and I aim, therefore, to cover all such modifications and variations as fall within the scope of my invention which is defined in the appended claims.

What I claim as new and desire to secure by Letters Patent of the United States is:

1. A telemetering system comprising a source of direct current, one side of which may be grounded, a transmitter, a receiver, and a pair of conductors, the transmitter comprising a resistor grounded at one end with a terminal at the other end and a tap movable in response to indications to be transmitted, said terminal and said tap respectively connected to the first and second of said conductors, said current source being grounded on one side and having its ungrounded side connected to the first of said conductors, said receiver comprising an annular core of magnetizable material, a transversely magnetized permanent magnet rotor rotatably mounted within said annular core substantially concentric therewith, and a pair of windings linking said core, said windings being connected in series opposition with respect to flux flow circularly through the core and having a junction point connected to the second of said conductors, the first of said conductors being connected to the free end of one of said windings, the free end of the other of said windings being grounded, whereby said resistor shunts the current source and the series connected windings, and adjustment of the tap on said resistor varies the relative strength of the currents flowing in said windings to cause variation in angular direction of the flux produced by the stator windings diametrically crossing the stator core, thus in turn, determining the angular position of the rotor.

2. A receiver for a direct-current telemetering system of the type including means for transmitting to a receiver a pair of series connected voltages adjustable in relative magnitude, said receiver comprising an annular core with an air gap therein, a pair of windings linking said core, and a rotor substantially concentrically mounted within said core and magnetized transversely to its axis of rotation and the axis of the annular core, said windings being connected in series opposition with respect to flux flowing circularly within the core, said coils having end terminals and a junction serving as a mid terminal, whereby the series connected transmitted voltages of the telemetering system may be applied to said coils respectively, the length of the air gap in the core being such that leakage flux passing diametrically across the stator core suffers no excessive variation in magnitude with variation in relative magnitude of said voltages, the angular direction of said diametrical flux changing in accordance

10 with the relative voltages existing across the said coils, whereby the angular position of the rotor may be varied.

3. A receiver for a telemetering system comprising an annular core of magnetizable material and a permanent magnet rotor mounted rotatably with respect to an axis substantially concentric with said core, said stator core carrying a pair of electrical coils connected in opposition and adapted to have voltages applied thereto adjustable in ratio, said coils being mounted on different portions of the annular core with the center portions of the coils less than 180 degrees apart on the annular core, whereby the currents caused to flow in said coils by said applied voltages produce magnetomotive forces acting in opposition circularly in the annular core to cause magnetic flux to cross the annular core diametrically, the angular direction of the magnetic flux at the center of the annulus varying in accordance with the relative strengths of currents in said coils to cause deflection of the permanent magnet rotor in accordance with the variation in the relative strengths of voltages applied to said coils.

4. A receiver for a direct-current telemetering system of the type including means for transmitting to a receiver a pair of series connected voltages adjustable in relative magnitude, said receiver comprising an annular core, a pair of windings linking said core, and a rotor substantially concentrically mounted within said core and magnetized transversely to its axis of rotation and the axis of the annular core, said windings being connected in series opposition with respect to flux flowing circularly within the core, said coils having end terminals and a junction serving as a mid terminal, whereby the series connected transmitted voltages of the telemetering system may be applied to said coils respectively, the angular direction of said diametrical flux changing in accordance with the relative voltages existing across the said coils, whereby the angular position of the rotor responds to the relative magnitude of said voltages.

5. A receiver for a direct-current telemetering system of the type including means for transmitting to a receiver a pair of series connected voltages adjustable in relative magnitude, said receiver comprising substantially annular magnetic core means, a pair of electrical windings linking said core means, a rotor mounted between said windings substantially concentric with the core means, said windings being connected in series opposition with respect to a magnetic circuit including both of them, and being mounted with their magnetic axes at an angle to each other, said magnetic core means including a portion providing a sufficiently low reluctance path between said windings to cause leakage flux to travel in said path between said windings diametrically across the core and to intersect said rotor, said coils having end terminals and a junction serving as a mid terminal, whereby the series connected transmitted voltages of the telemetering system may be applied to said coils respectively, the angular direction of said leakage flux changing in accordance with the relative voltages existing across said coils, whereby the angular position of the rotor responds to the relative magnitudes of said voltages, the length and reluctance of the diametrical flux path being substantially the same for various angles owing to the annular shape of the core means.

RICHARD G. JEWELL.
